SLIDE MOUNTING

Filed Dec. 13, 1946

UNITED STATES PATENT OFFICE

2,548,712

SLIDE MOUNTING

Fred Firmin, Detroit, Mich., assignor to Modern
Collet & Machine Company, Ecorte, Mich., a
corporation of Michigan

Application December 13, 1946, Serial No. 716,123

1 Claim. (Cl. 308—3)

1

My invention relates to a new and useful improvement in a slide mounting for use on metal working machines in which the metal working tools are carried on a slide.

It is an object of the present invention to provide a slide mounting whereby an accurate adjustment of the slide may be easily and quickly determined. Another object of the invention is the provision of a slide mounting so arranged and constructed that accuracy may be maintained during the working operation.

Another object of the invention is the provision of a slide mounting so arranged and constructed that wear which may take place between the slide and the slide block may be easily and quickly compensated for.

Another object of the invention is the provision of a slide block mounting so arranged and constructed that a maximum area of contact may be provided between the slide blocks and the slide.

Another object of the invention is the provision of a slide mounting cooperating with the slide block so arranged that an easy and quick assembly may be made.

Other objects will appear hereinafter.

It is recognized that various modifications and changes may be made in the detail of structure illustrated without departing from the invention itself and it is intended that such shall be embraced within the scope of the claim which forms a part hereof.

Forming a part of this specification are drawings in which:

Fig. 1 is a top plan view of the invention with parts broken away and parts shown in section.

Fig. 2 is a front elevational view of the invention.

Fig. 3 is a sectional view taken on line 3—3 of Fig. 2.

Fig. 4 is a sectional view taken on line 4—4 of Fig. 3.

As shown in the drawings the invention embodies a slide block 9 having openings 12a formed therethrough through which are extended screws 12 whereby the slide block 9 may be securely fastened to the bed or supporting structure 10 shown in dotted lines in Fig. 4 and in Fig. 2. This slide block 9 is formed V-shaped at its opposite longitudinal edges to provide the inclined faces 13 and 14 on one side and 15 and 16 on the opposite side. An adjusting block 17 is provided with a V-shaped groove on one side to provide the faces 18 and 19 which are adapted

5 to bear against the faces 13 and 14 respectively of the slide block 9.

A slide 20 is provided having the transversely extended T-slots 21 in which are fastened securing means to secure the tool post in position on the slide. This slide 20 is provided on its opposite sides with the depending portions 20a and 20b. Formed in the upper face of the slide block 9 is a recess having the face 11, this recess being in registration with the recess 46 formed in the under side of the slide 20. Engaging in these recesses is a presser plate 22. As shown clearly in Fig. 3, the face 46 is horizontal and the face 11 inclined so that the thickness vertically of the combined recesses diminishes toward the rear of the machine. Engaging in these recesses is a presser plate 22 which is thicker at its outer end than at its inner end. The face 24, as shown in Fig. 3, is complimentary to the face 11 so that the face 23 is a horizontal face and lies in engagement with the horizontally positioned face 46 of the slide 20. Projecting downwardly from the outer end of the plate 22 is a boss 26 having a passage formed therethrough and through which is extended a threaded stud 27 threaded into the socket 28 formed in the slide block 9. Threaded on this stud 27 are the lock nuts 29 and 30. The arrangement is such that as the plate 22 is thrust inwardly it will 10 serve to clamp the faces of the V-groove 35 against the faces 15 and 16 of the slide block and, likewise, serve to clamp the faces 13 and 14 against the faces 18 and 19.

Formed in the depending portion 20a of the slide is a recess having the faces 33 and 31 and engaging in this recess is the block 17. The bottom of the block 17 bears against the inner face of the securing plate 41 which is secured to the portion 20a by means of screws 42. The face 34 of the presser block 17 bears against the face 31 and as shown in Fig. 1, these faces 31 and 34 incline so that the thickness of the block 17 diminishes proceeding inwardly from the outer end. Threaded into the socket 38 15 formed in the depending portion 20a is a stud 37 which projects through a passage formed in the boss 36 extending laterally from the block 17. Lock nuts 39 and 40 are threaded on this stud 37. The construction is such that upon 20 sliding the block 17 inwardly it may be locked in position by means of the lock nuts 39 and 40 and this inward sliding may be effected by loosening the nut 39 and threading the nut 40 to force the block 17 inwardly. As this block 17 moves inwardly it will move laterally into closer

engagement with the slide block 9 and into closer engagement with the faces 31, 32, and 33, while at the same time drawing the faces of the V-groove 35 into closer contact with the faces 15 and 16.

I have thus provided a means whereby the slide 20 may be easily and quickly released for sliding movement on the slide block 9 and easily and quickly secured in the proper adjusted position. It will be noted that when the presser plate 22 is used for exerting pressure, the pressure on the slide block 20 will be upwardly and there will also be a lateral pressure on the depending portions 20a and 20b by virtue of their pressing action against the faces 13, 14, 15, and 16. Likewise, when the presser plate, or V-block 17, is used for exerting pressure, the pressure will be directed laterally and upwardly and downwardly. This makes it possible to lock the slide 20 in position without in any manner disturbing the position to which it may have been adjusted. Consequently, it is possible with a slide mounting of this class to adjust the slide to very fine adjusted positions. It will also be noted that the bearing surfaces provided are the areas of the faces 13, 14, 15, and 16, against the corresponding faces in the portion 20b and in the V-block 17 which, in turn, transmits the pressure to the faces 31, 32, and 33. Pressure will also be exerted on the face 46 so that a maximum area of contact is thus provided which is important in securing fixedly a slide on its mounting and preventing a disturbance of that adjusted position in which it may be secured.

What I claim is:

A device of the class described comprising: a slide block having oppositely disposed side faces, each formed V-shaped in cross-section; a slide positioned over said slide block and having a

V-shaped groove for engaging and conforming to the surface of one of the side faces of said slide block, said slide block having a longitudinal recess formed on its upper face, registering with a longitudinal recess formed on the lower face of said slide; a presser plate positioned in said recesses and moveable longitudinally therein, said presser plate having an inclined face engaging an inclined face in one of said recesses and effecting, upon longitudinal movement in one direction, a separating pressure between the lower face of said slide and the upper face of said slide block for pressing the faces of said V-shaped groove against the side face of the slide block engaging in said groove; and means engageable with said presser plate and said slide block for effecting longitudinal movement of said presser plate; a presser block having a V-shaped groove for engaging the opposite side face of said slide block and seated in a recess formed in said slide and adapted, upon longitudinal movement, for exerting a separating presser between the bottom of said last named recess and the engaged face of said slide block; and means engageable with said presser block and said slide for effecting longitudinal movement of said presser block.

FRED FIRMIN.
